UNITED STATES PATENT OFFICE.

FRED PFAUS AND AUGUST PFAUS, SR., OF NEWARK, NEW JERSEY.

BRACELET CONSTRUCTION.

1,406,073.

Specification of Letters Patent.

Patented Feb. 7, 1922.

Application filed March 12, 1921. Serial No. 451,900.

To all whom it may concern:

Be it known that we, FRED PFAUS and AUGUST PFAUS, Sr., citizens of the United States, residing at Newark, in the county of 5 Essex and State of New Jersey, have invented new and useful Improvements in Bracelet Construction, of which the following is a specification.

The object of our present invention is the 10 provision of a strong and durable bracelet construction, designed more especially, though not necessarily, for use in conjunction with a wrist watch to fasten the latter on the wrist, and one in which very little 15 precious metal need be employed notwithstanding the fact that all of the exposed portion of the construction is preferably formed of precious metal.

To the attainment of the foregoing, the 20 invention consists in the improvement as hereinafter described and definitely claimed.

In the accompanying drawings, forming part hereof:—

Figure 1 is a plan view showing our novel 25 bracelet construction as attached at its ends to a wrist watch.

Figure 2 is a longitudinal central section taken through the bracelet construction.

Figure 2^a is a fragmentary edge elevation 30 of the bracelet construction showing the extent to which two of the hollow exterior members of the bracelet construction are adapted to flex relatively to the similar member between them.

Figure 3 is an enlarged interior view of 35 the bracelet construction.

Figure 4 is a transverse section taken on the line 4—4 of Figure 3, looking toward the right.

Figure 5 is a perspective of one of the 40 links comprised in the bracelet construction and which may be made of any inexpensive strong metal or alloy appropriate to its purpose.

Figure 6 is an inverted perspective on an 45 enlarged scale of one of the hollow exterior members of the bracelet construction, as said member precedent to the flaring thereof.

Figure 7 is a perspective showing one of 50 the link connectors of the construction as said connectors appear precedent to being bent into loop form shown in Figures 3, 4 and 5.

Similar numerals of reference designate 55 corresponding parts in all of the views of the drawings.

The wrist watch 1 illustrated is not of our invention, and we would have it distinctly understood that without involving departure from the scope of our invention our bracelet 60 construction may be fastened at its ends to the wrist watch in any appropriate manner. We would also have it distinctly understood that it is within the purview of our invention to embody our novel construction in a 65 bracelet per se—i. e., a bracelet that is endless or one the ends of which are adapted to be connected together in any appropriate manner.

The bracelet construction which constitutes our real invention is made up of links 70 3 which may be and preferably are formed of strong metal, connectors 4 which may be and preferably are also formed of strong metal, and exterior hollow members 5 which 75 may be and preferably are formed of gold or some other precious metal. Our invention contemplates the removal of all strain from the members 5 notwithstanding the 80 said members 5 are strongly connected together in a longitudinal series, and from this it follows that the members 5 may be made very thin so that the bracelet will present the appearance of an expensive bracelet, and yet may embody but a very small quantity 85 of precious metal. It will be observed by comparison of Figures 1 to 6 that the links 3 are open links, and that the connectors 4 are nothing more than strips of strong thin metal bent into loop form so as to 90 hingedly connect the contiguous transverse bars of adjoining links 3; and it will also be noticed that the members 5 are each provided with an outer wall or body 6, transverse or end walls 7 in which are openings 8, 95

and side walls 9 the inner corners of which are beveled as indicated by 10. The links 3 are arranged one in each member 5, and the connectors 4 are adapted to embrace the end bars of adjoining links as well as the end 100 bars 7^a of adjoining members 5. It will also be observed that the walls 9 of the members 5 are provided with inwardly directed flanges 11, arranged flush with the exposed sides of the connectors 4 so that the bracelet 105 construction will have a smooth inner surface and hence will not be liable to scratch or chafe the wrist of the wearer. Manifestly when the flanges 11 are turned inwardly at right angles to the major portions 110 of the walls 9, the bevels 10 will form between them angular spaces 12 such as shown

in Figure 3. In consequence of this the bracelet construction is adapted to flex to approximately the extent illustrated in Figure 2^a, and from this it follows that the bracelet construction as a whole is flexible and may be made to conform comfortably to the wrist of the wearer.

Manifestly it is within the purview of our invention to make the connectors 4 or portions of said connectors 4 of precious metal so that the portions of the connectors exposed between the ends of the members 5 when the bracelet is flexed will not detract from the finished appearance of the bracelet.

Having described our invention, what we claim and desire to secure by Letters-Patent, is:—

1. A bracelet construction comprising open links, hollow exterior members each receiving one link and having end bars, and connectors each receiving the end bars of contiguous end bars of adjoining links and the contiguous end bars of adjoining hollow exterior members.

2. A bracelet construction comprising open links, hollow exterior members each receiving one link and having end bars, and connectors each receiving the end bars of contiguous end bars of adjoining links and the contiguous end bars of adjoining hollow exterior members; the hollow exterior members also having flanges reaching inwardly from their side walls and arranged flush with the connectors, and the connections between the links and the hollow exterior members being flexible.

3. A bracelet construction comprising open links, hollow exterior members each receiving one link and having end bars, and

connectors each receiving the end bars of contiguous end bars of adjoining links and the contiguous end bars of adjoining hollow exterior members; the hollow exterior members having flanges reaching inwardly from their side walls and arranged flush with the connectors and also having the ends of said flanges beveled.

4. A bracelet construction the exterior of which is formed of members of relatively precious metal and the interior of which is formed of a chain, whereby the exterior members are flexibly connected together without liability of strain being imposed on the same.

5. A bracelet construction the exterior of which is formed of members of relatively precious metal and the interior of which is formed of a chain, whereby the exterior members are flexibly connected together without liability of strain being imposed on the same; the said exterior members covering the chain at the outer side and side edges of the bracelet.

6. A bracelet construction the exterior of which is formed of members of relatively precious metal and the interior of which is formed of a chain, whereby the exterior members are flexibly connected together without liability of strain being imposed on the same; the said exterior members covering the chain at the outer side and side edges of the bracelet, and being provided with inwardly directed longitudinal flanges arranged flush with portions of the chain.

In testimony whereof we affix our signatures.

FRED PFAUS.
AUGUST PFAUS, Sr.
